J. T. Packard,

Organ Bellows.

No. 9290.

Patented Sep. 28, 1852.

UNITED STATES PATENT OFFICE.

ISAAC T. PACKARD, OF CAMPELLO, MASSACHUSETTS.

BELLOWS FOR REED INSTRUMENTS.

Specification of Letters Patent No. 9,290, dated September 28, 1852.

To all whom it may concern:

Be it known that I, ISAAC T. PACKARD, of Campello, in the county of Plymouth and State of Massachusetts, have invented 5 certain new and useful Improvements in Bellows for Melodeons and other Reed Musical Instruments; and I do hereby declare that the following is a full, clear, and exact description of the same, reference being had 10 to the accompanying drawings, forming part of this specification, in which—

Figure 1, is a transverse section of a double action bellows, and other parts of a melodeon, and, Fig. 2, is a plan of the bellows with the upper leaf removed.

Similar letters of reference indicate corresponding parts in each figure.

The nature of this invention consists in constructing the bellows with two chambers 20 and a pump furnished with valves so arranged that when they are set in operation, the air is exhausted from one chamber and condensed in the other. There is a communication between the two chambers 25 through the reeds, when the valves upon which the reeds operate are opened by pressing on the keys, and air is forced through the reeds from the condenser, while at the same time it is, as it were, drawn through 30 by the vacuum in the exhaust chamber, by which means the sound is produced more quickly and the tone is better in every respect than that produced by forcing or drawing alone.

35 To enable those skilled in the art to make and use my invention I will proceed to describe its construction and operation.

40 A, is a board which is secured to the frame of the instrument and forms the division between the exhaust and condensing chambers.

45 E, is the exhaust chamber; C, the condensing chamber and P, the pump, all of which are formed by leaves in a similar manner to the chambers of other bellows. The exhaust chamber and pump are furnished with springs *a*, *a'*, inside to open them, and the condenser with a spring *b*, outside to close it. There are communications between the exhaust chamber and the pump, which are 50 closed by the valves *d*, opening toward the pump, and other communications between the condenser and pump closed by a valve or valves *e*, opening from the pump. The back of the condenser terminates in a flexible joint *h*, leaving a passage behind it for

communication between the exhaust chamber and pump. There is a communication between the condenser and exhaust chamber closed by a valve *f*, which opens toward the condenser and has a string *g*, attached to it connecting it to the movable leaf, *B*, of the condenser—this latter is a safety valve. All the valves consist of strips of leather secured at each end over a series of holes.

D is one of the reeds, and F, the valve 60 which opens the communication through it; between the exhaust chamber and condenser, is the key *K*.

J, is the sounding board which is thin and fitted air tight over the reeds.

G, is the swell valve which is opened by a wire *i*, passing out through the back of the bellows, and intended to be connected to a foot pedal.

H, is treadle and I, a rod for working the 75 bellows.

When the player presses down the treadle, it lifts up the bottom of the pump P, closes the valve *d*, and opens that at *e*, forcing all the air previously contained in the pump 80 into the condenser C; when the pressure of the foot is removed and the treadle allowed to rise, the spring *a'* opens the pump and causes the valve *e* to close, and *d*, to open, 85 the air then rushes from E, which begins to collapse into P, which is filled. The next downward movement of the treadle forces the air now contained in P, into C, and the next upward motion again fills P, from E, 90 in this way a vacuum is produced in E, and C, is filled and the air compressed in it by the closing tendency of the spring *b*. The chamber E, has always an inclination to distend itself, produced by the spring *a*, and the instant the valves E, communicating 95 with the reed are opened by the keys the pressure in C, forces air through, while the vacuum and opening tendency of E, at the same time draw it through, and thus produces the vibration. If the bellows were to continue working for a length of time without opening the valves F, an undue strain would be produced in the chamber—to obviate this the safety valve *f*, is connected to the lower side of the condenser by the string *g*, 100 which is of such length that when the condenser is distended or opened to a certain width it pulls the valve open and admits air into E, this will always happen when the condenser is unduly strained. It will be 105 110

observed that no air is admitted from the exterior of the bellows, from the exhaust chamber to the condenser, through the valves *d*, and *e*, and from the condenser back 5 to the exhaust chamber through the reeds, or through the safety valve.

The peculiarity of these bellows is that they act upon the reeds in two ways namely by forcing and drawing the air through 10 them. The advantages thus produced are that the sound is produced more instantaneously on pressing down the key. The quality of the tone is greatly improved, being full, rich, and mellow throughout the 15 scale with little or none of the reedy character found in reed instruments with the forcing bellows only, and without the nasal quality which predominates where the air is only drawn through the reeds.

What I claim as my invention and desire 20 to secure by Letters Patent, is—

The employment in all reed musical instruments of bellows having two chambers, in one of which a vacuum is produced, and in the other air is compressed, the said 25 chamber being on opposite sides of the reeds and communicating with each other through the reeds so that when one forces air through them the other by the vacuum draws it through at the same time—this I 30 claim without reference to the precise construction of the bellows or the mode of operating them.

ISAAC T. PACKARD.
